STICK FOR CATHODE PLATES

Michael Tetrault, Great Falls, Mont.

Application April 15, 1941, Serial No. 388,705

5 Claims. (Cl. 204—297)

This invention relates to apparatus for use in electrolytic processes, but more particularly to an edge protecting member designed primarily for use in connection with cathode plates, but it is to be understood that an edge protecting member in accordance with this invention is for employment in any connection for which it may be found applicable.

The invention forming the subject matter of this application is a continuation in part of my application filed November 16, 1938, Serial No. 240,814, allowed November 19, 1940.

In the practice of certain electrolytic processes, particularly those relating to the electrolytic deposition of metals, such as zinc and copper, it is important that an edge protector be provided to prevent the metal from forming completely around the cathode plate. Generally for this purpose a strip, or what is called a stick, is employed, and it is in the form of a strip of wood, 20 longitudinally grooved, the width of the groove being slightly less than the thickness of the cathode plate. The stick is forced onto the plate, from an edge of the latter and held frictionally in position by the walls of the groove. Sticks 25 of such type when used often become detached from the plate, warped, rotted, split and cracked due to the action of the electrolyte which renders them useless.

The stick forming the subject of this invention is not only an improvement upon the form of stick aforesaid, but also the stick disclosed by U. S. Letters Patent 1,977,499 and Canadian Patent 367,412 granted to me. The stick, in accordance with this invention not only embodies all the aims, advantages and objects as set forth by the Letters Patent aforesaid, but further aims to so construct a stick of the gripping type whereby its durability and strength is materially increased; enhancing and maintaining its gripping characteristic to an extent greater than such characteristic possessed by other forms of sticks; capable of being detached from one plate and positioned in gripping relation with respect to another plate, having a metallic core encased 45 by an insulating covering possessing a solid gripping characteristic; capable of being readily attached to the top, bottom and sides of a plate when desired; and when used permitting of the metal, deposited onto the plate to be easily 50 stripped off.

The invention further aims to provide, in a manner as hereinafter set forth, a stick for the purpose referred to formed of a composite lengthwise grooved body including a core encompassed 55

by an insulating cover, with the core being so disposed relatively to the cover, to provide the latter with a pair of resilient portions functioning to frictionally grip the stick to the plate, and with said portions of a thickness to compensate for wear, when connecting the stick to and removing it from the plate whereby the life of the stick for its use will be materially increased.

Embodying the aforesaid aims, and others which may directly or indirectly hereinafter appear, the invention consists of the novel construction, combination and arrangement of parts, as will be more specifically described and illustrated in the accompanying drawing, wherein is shown embodiments of the invention, but it is to be understood that changes, variations and modifications may be resorted to which fall within the scope of the invention as claimed.

In the drawing:

Figure 1 is an elevation of a cathode plate showing the adaptation with the marginal portions and edges thereof a stick in accordance with this invention.

Figure 2 is a fragmentary view, in section of one corner of the structure shown in Figure 1.

Figure 3 is a view similar to Figure 1 of a modified form of stick, in accordance with this invention.

Figure 4 is a view similar to Figure 2 of one corner of the structure shown in Figure 3.

Figure 5 is a section on lines 5—5 Figures 1 and 3 showing the transverse cross sectional contour of the sticks.

Figure 6 is a detail front elevation of a pair of sticks used on opposite sides of a plate which is longer than the length of the sticks and used in zinc plating.

Figure 7 is another form of stick structure used in copper plating, and

Figure 8 is a fragmentary view in vertical section of a pair of abutting sticks, in accordance with this invention, illustrating the manner by which the sticks maintain an anode in spaced relation with respect to a cathode to prevent short circuiting.

The stick may be of a length slightly less or slightly greater than the length of any one of the edges of the cathode plate, as is shown by Figure 1 or of a length corresponding to the combined length of the edges of the cathode plate as is shown by Figure 3. In Figures 1 and 2, the stick is generally indicated at 6, in Figures 3 and 4 at 7, in Figure 5 at 8. In Figures 1 to 7 of the drawing the cathode plate is correspondingly

designated 8^a. By way of example, plate 8^a is illustrated as of rectangular contour.

With reference to the sticks 6, 7 and 8 they include metallic cores 9, 10, 11 respectively and insulating elastic plate gripping covers 12, 13 and 14 for the cores 9, 10, 11 respectively. The transverse cross sectional contours of the said cores are the same. The transverse cross sectional contours of the covers are the same. The shape of each of the cores in transverse cross section and the shape of each of the covers in transverse cross section is shown by Figure 5.

Each core, with reference to Figure 5 is of substantially yoke-shaped form and consists of a pair of spaced aligned side parts 15, 16 disposed at opposite outward inclinations from their inner to their outer ends, and a coupling part 17 disposed at right angles to and merging into the inner ends of the side parts 15, 16. This manner of setting up the core provides its outer or open end of a greater width than its inner or closed end, or in other words the core is of a form which flares from its inner or closed end to its outer or open end. The corners 18 of the core, at the points of emergence of the side parts 15, 16 with the coupling part 17 are rounded. Preferably, the body of the core will be of uniform thickness and will be set up from any suitable metallic material, preferably aluminum.

Each cover, with reference to Figure 5 is of substantially yoke-shaped form and consists of a pair of spaced aligned side parts 19, 20 and a coupling part 21 disposed at right angles to and merging into the inner ends of said side parts. The parts 19, 20, 21 coact to provide a groove 22 having a flat base wall 23 and a pair of side walls 24, 25 of greater width than the base wall. The side walls are oppositely outwardly inclined to an extent to provide for the mouth of the groove to be slightly wider than the base wall 23. The cover is formed of any suitable insulating material possessing an elastic characteristic whereby the cover will embody a gripping function, and preferably, the cover will be formed of rubber. The cover in transverse cross section is of greater length than the transverse cross sectional length of the core.

The core is embedded in the cover in a manner to have its coupling part 17 positioned centrally with respect to the coupling part 21 of the cover, such as shown in Figure 5. When the core is embedded in the cover, its side parts 15, 16 will be disposed at opposite outward inclinations within the side parts of the cover, and with the said side parts of the core positioned a greater distance from the side walls 24, 25 of the groove 22 than the distance between the core side parts and the other side surfaces 26 of the cover. The outer ends of the core side parts will be spaced inwardly adjacent to the end surfaces 27 of the cover side parts. The manner of setting up the core with respect to the cover provides the cover side parts with thick elastic gripping portions 28 whereby the life of the latter will be increased.

When a stick is active, it is mounted through the medium of the groove 22 upon the cathode plate in a manner to have an edge of the latter abut the groove base wall and opposite marginal portions of the plate bear on the side walls of the groove, and due to the action of the gripping portions 25, they will tightly grip the said marginal portions of the cathode plate whereby the stick and the plate will be secured together by a frictional latch. The providing of the mouth

of the groove slightly wider than the base wall 23 facilitates the positioning of the stick on the plate and reduce wear on the gripping portions 28 as the plate is inserted into the groove.

5 The cover 12 for the core 9 is to completely encase the latter, that is to say the cover 12 not only encompasses the coupling and side parts of the core, but also has the ends of the latter embedded herein. One or a plurality of sticks 6 10 may be secured to cathode plate. When a plurality of sticks 6 are employed they are mounted on the lengthwise and side edges of the plate as is shown by Figure 1. The sticks 6 which are to be mounted on the lengthwise edges of the plate 15 are to be of less length than the length of such edges, and the sticks 6 mounted on the side edges of the plate are to be of greater length than the length of such edges, and of a length to abut the ends of the sticks 6 mounted on the lengthwise edges of the plate.

20 The stick 7 is to be of a length whereby it may be bent in the form of a frame corresponding in contour to the shape of the cathode plate, and the frame is to be of a size to be mounted on the plate in overlapping relation with respect to the lengthwise and side edges of the plate, as is shown by Figure 3. When stick 7 is set up in frame-like form it is formed with spaced inwardly opening notches 29 and has its ends mitered as at 30 whereby when the frame is formed it will have perfect corners. After the frame has been formed and mounted in the cathode plate the edges of the mitered ends and the edges of the notches are vulcanized together.

30 The stick 8 may be of the length and form corresponding to stick 6 or of a length and form corresponding to stick 7.

35 When the cover is formed of other material than that of rubber, it is secured to the core 40 by any suitable means, but when formed of rubber it is vulcanized to the core.

45 In Figure 6 there is disclosed a pair of sticks 6^a which are positioned on opposite sides of the plate 8^a. The sticks 6^a are similar in every detail to the stick disclosed in Figure 5, but in the present instance, the sticks 6^a have a length relatively shorter than the length of the plate 8^a and this construction has been found particularly adapted for use in zinc plating. The zinc deposit on the plate 8^a can be stripped therefrom more readily than a copper deposit and for this reason a bottom edge stick is not necessary for zinc plating. In copper plating where the edges of the cathode plate are not encased, the copper plating will completely encase the cathode plate thereby making it difficult to strip the copper from the plate. The sticks 6^a prevent the formation of the zinc on the longitudinal edges of the plate 8^a.

50 In Figure 7 there is disclosed a further modification of stick structure wherein sticks 6^b are positioned on the opposite longitudinal edges of the plate 8^a and there is also positioned an end stick 6^c at the lower end of the plate 8^a. This 55 U-shaped arrangement of the stick structure has been found particularly adaptable in copper plating so as to prevent the accumulation of copper at the lower end and at the longitudinal edges of the plate 8^a. The sticks 6^b and 6^c are mounted 60 on the plate by pressing the sticks inwardly of the edges thereof, the channel in each stick being of such a width that the plate will be firmly gripped by the opposite sides of the stick. The metal core of each stick will effect a firm grip on the opposite sides of the plate at all times. The 65

sticks 6^b and 6^c are similar in every detail to the stick disclosed by Figure 5.

With reference to Figure 8, sticks 31, 32 are of the same construction as the stick 8, as shown. The stick 31 is attached on an anode 33 and the stick 32 on a cathode plate 34. The sticks 31, 32 are in abutting relation and owing to the manner in which they are constructed, anode 33 is spaced from the plate 34 to prevent short circuiting.

What I claim is:

1. In a removable stick for a cathode plate, a composite rectangular body comprising a metallic core and an elastic cover of non-conducting material for the core, said core being of yoke-shaped contour having its open end of greater width than its closed end and consisting of a pair of spaced opposed upstanding straight side parts of like form disposed at opposite outward inclinations and a horizontal coupling part merging into corresponding ends of said side parts, the transverse cross sectional length of each of said side parts being uniform throughout, said cover being of yoke-shaped contour having its open end corresponding in width to its closed end and consisting of a pair of spaced parallel upstanding side portions of like form and a horizontal coupling portion merging into corresponding ends of said side portions, the transverse cross sectional length of each of said side portions being uniform throughout, the thickness of each of said side portions being uniform throughout, said side portions completely encompassing and binding throughout against said side parts, said coupling portion completely encompassing and binding throughout against said coupling part, said coupling portion bridging the space between said side portions, the inner surfaces of said side and coupling portions being so related to form the cover with a groove for mounting the stick on the plate, and the said inner surfaces forming the walls and bottom of said groove for frictional engagement with the plate to thereby connect the latter to the stick.

2. An edge encasing member for a cathode plate comprising a metallic core having a U-shaped contour in transverse section, the sides of the core diverging from the bight thereof, and a rubber covering encompassing said core, said covering being of U-shaped contour in transverse section and forming a plate receiving groove insulated from said core, that portion of the covering disposed inwardly of the inner surfaces of the sides of the core being of greater thickness than that portion of the covering which is disposed outwardly of the outer surfaces of the sides of the core the thickness of the covering on the inner sides of the core increasing in thickness from the bight to the ends of the di-

vergent legs thereof with the confronting portions of said covering in parallelism.

3. In combination, a rectangular cathode plate and a rectangular frame about the marginal edges of the plate, said frame comprising a metallic core having a U-shaped contour in transverse section, the sides of the core diverging from the bight thereof, and a rubber covering encompassing said core, said covering being of U-shaped contour in transverse section and forming a plate receiving groove insulated from said core, that portion of the covering disposed inwardly of the inner surfaces of the sides of the core being of greater thickness than that portion of the covering which is disposed outwardly of the outer surfaces of the sides of the core the thickness of the covering on the inner sides of the core increasing in thickness from the bight to the ends of the divergent legs thereof with the confronting portions of said covering in parallelism.

4. A cathode plate stick comprising a member U-shaped in side elevation and also U-shaped in transverse section, said member comprising a metallic core having a U-shaped contour in transverse section, the sides of the core diverging from the bight thereof, and a rubber covering encompassing said core, said covering being of U-shaped contour in transverse section and forming a plate receiving groove insulated from said core, that portion of the covering disposed inwardly of the inner surfaces of the sides of the core being of greater thickness than that portion of the covering which is disposed outwardly of the outer surfaces of the sides of the core the thickness of the covering on the inner sides of the core increasing in thickness from the bight to the ends of the divergent legs thereof with the confronting portions of said covering in parallelism.

5. A cathode plate stick comprising a member rectangular in side elevation and U-shaped in transverse section, said member comprising a metallic core having a U-shaped contour in transverse section, the sides of the core diverging from the bight thereof, and a rubber covering encompassing said core, said covering being of U-shaped contour in transverse section and forming a plate receiving groove, insulated from said core, that portion of the covering disposed inwardly of the inner surfaces of the sides of the core being of greater thickness than that portion of the covering which is disposed outwardly of the outer surfaces of the sides of the core the thickness of the covering on the inner sides of the core increasing in thickness from the bight to the ends of the divergent legs thereof with the confronting portions of said covering in parallelism.
